UNITED STATES PATENT OFFICE.

THOMAS L. ARTHUR, OF EAST SMETHPORT, PENNSYLVANIA.

ROTARY GAS-ENGINE.

1,219,795.

Specification of Letters Patent.

Patented Mar. 20, 1917.

Application filed March 7, 1916. Serial No. 82,719.

To all whom it may concern:

Be it known that I, THOMAS L. ARTHUR, a citizen of the United States, residing at East Smethport, in the county of McKean and State of Pennsylvania, have invented certain new and useful Improvements in Rotary Gas-Engines, of which the following is a specification.

My invention relates to new and useful improvements in internal combustion engines and more particularly to rotary engines of the type in which a plurality of cylinders are radially disposed about a common crank shaft, the crank shaft being held 10 in a stationary position and the cylinders and crank case revolving about it when the engine is in operation, one of the primary objects of my invention being the provision of an engine of the above described character in which the crank case and cylinders are braced by and also inclosed in a frame which turns with them and with the cylinders constitutes a fly wheel.

A still further object of my invention consists in the provision of a novel means for positively operating the valves which control the intake of explosive mixture to the various cylinders and which govern the escape of exhaust gases from the several cylinders.

A still further object of my invention consists in the provision of a novel means for driving the magneto of an engine of the above described type, and in the provision 35 of a mechanism for automatically advancing and retracting the spark proportionate to the speed of the engine.

A still further object of my invention consists in the provision of a novel means for 40 supplying the explosive mixture to the engine cylinders, removing the exhaust gases therefrom, and supplying lubricating oil to the crank casing.

With these and other objects in view, my invention will be more fully described, illustrated in the accompanying drawings, and then specifically pointed out in the claims which are attached to and form a part of this application.

50 In the drawings:

Figure 1 is an elevational view of the

front or intake side of an engine constructed in accordance with my invention;

Fig. 2 is a vertical transverse sectional view through the engine;

Fig. 3 is a longitudinal sectional view taken centrally of the engine;

Fig. 4 is a fragmentary inner plan view of one of the gear driven controlling cams for operating the inlet and exhaust valves 60 of the engine.

Fig. 5 shows a modified form of construction in which the engine may act as a propeller or fan.

Corresponding and like parts are referred 65 to in the following description and indicated in all the views of the drawings by the same reference characters.

My improved engine may be supported by any type of frame, such as indicated by the 70 numeral 10, the frame, in any instance, being provided with horizontally aligned spaced bearings 11, one of which rotatably receives a sleeve 12 formed centrally of the rear wall of the crank casing 13 and the other of 75 which is adapted to receive and hold against rotation the forward end of the crank shaft 14 which is journaled in a relatively short sleeve formed centrally of the front wall of the casing. This crank casing 13 includes 80 a substantially cylindrical portion and radially extending arms, being for a four-cylinder engine of the type illustrated, cross-shaped as shown in Figs. 1 and 2 of the drawings with the arms of the cross open 85 at their ends. Preferably, one of the walls of the crank case is separable from the remainder of the case, being secured by bolts in the manner shown, and either or both of the walls may be formed with hand openings closed by plates 15, these openings permitting ready access to the interior of the crank casing. The sleeve 12 is preferably closed at its outer end and, formed at such end with an attaching flange 16 by means 90 of which it may be connected to a drive shaft 17, clutch or other desired mechanism, as power is transmitted from the engine by the rotation of the sleeve 12.

The crank shaft is formed within the 100 crank casing with a single crank arm 18 to which is connected the piston rods 19 carry-

ing the pistons 20 which operate in the engine cylinders 21. These engine cylinders are secured to the open ends of the arms of the crank casing by bolts 22 which are passed through peripherally extending flanges of the cylinders and corresponding flanges of the arms of the crank case and fastened by lock nuts. As will be noted, by reference to Fig. 3, the various piston rods 10 are offset somewhat intermediate their length in order that they may all be properly connected to their pistons and still operate with a common fixed crank shaft.

In order to provide proper lubrication, the bearing 11 is preferably formed with an annular chamber 23 to which leads an oil supply pipe 24 and the sleeve 12 is also formed interiorly with an annular chamber 25 which is in communication with the chamber 23 by 20 a plurality of radial ducts 26. That end of the crank shaft which is journaled in the sleeve 12 is formed centrally with a longitudinal oil passage 27 which opens radially into the annular chamber 25 of the sleeve 12 25 at one end and which opens at its other end into the crank case, as shown in Fig. 3.

The engine cylinders 21 are preferably of the T-head type having, at their outer ends, diametrically extended inlet valve chambers 28 and outlet valve chambers 29, the former being located at the front of the engine and the latter at the rear. The heads of the cylinders are preferably formed integrally with the bodies of the cylinders and are provided 30 with removable plugs 30 which will permit access to the valve chambers and valves controlled therein. The valve chambers are divided transversely by partition walls 31 formed with seats for the puppet valves 32 35 and 33 which control the inlet and exhaust of of the engine cylinders, the stems of these puppet valves extending through caps 34 threaded upon nipples 35 formed upon the inner walls of the valve chambers. The 40 valve stems, adjacent their outer ends, are perforated to receive pins 36 and helical springs 37 are located between these pins and the caps 34 to normally maintain the valves in closed position.

50 As a means for opening the valves against the action of their springs, at the proper times, I provide the crank case with a plurality of sleeve forming brackets 38 disposed one in alignment with each of the stems of 55 the valves 32 and 33. Rods 39 are slidably mounted in these sleeves and lightly engage the free ends of the valve stems when the valves are closed, being supported in such position by pins 40. The lower ends of these 60 rods are bifurcated to receive rollers 41 and these rollers project in the path of cams 42 carried upon the inner faces of spur gears or disks 43 mounted upon stub shafts 44 extending outwardly from the crank casing.

65 The spur gears 43, which control the inlet

valves 32, mesh with a pinion 45 fixed upon the crank shaft 14. The shafts carrying the disks 43 which control the exhaust valves 33 extend through the casing and carry spur gears 46 corresponding to the spur gears 43 and meshing with a pinion 47 fixed to the crank shaft within the crank casing. As my improved engine is of the four-cycle type, it will of course be understood that these gears and pinions are so arranged that each valve will be opened once during each two revolutions of its cylinder about the crank shaft. It will further be understood that when the inlet valve of one cylinder is opened, the exhaust valve of the cylinder diametrically opposite it will also be opened.

70 As a means for supplying an explosive mixture or gas to the inlet valve chamber of the various cylinders, the free end of the crank shaft is formed with a longitudinal chamber 48 opening through its end with radial passages 49 opening through its side into a hood or bonnet 50 which closely surrounds the shaft providing an annular chamber to receive gas admitted through a supply pipe 51 to the chamber 48. Branch supply pipes 52 lead from this hood or bonnet 50 to each of the intake valve chambers. In like manner, to lead off the exhaust gases from the various cylinders, I provide branch exhaust pipes 53 which lead one from each of the exhaust valve chambers to a hood or bonnet 54 fixed about the extended portion of the sleeve 12 of the crank shaft casing and providing a chamber 55 which communicates 80 with a corresponding chamber 56 formed in a second bonnet or hood 57 which is loosely mounted about the sleeve 12 and from which extends the main exhaust pipe 58.

85 As a means for igniting the explosive mixture after its admission to the various engine cylinders, each cylinder is provided with a spark plug 59 of any suitable type which may be threaded into the head of the cylinder or into the side thereof near its outer end, 90 as preferred. Conductor wires 60 lead from the spark plugs to the contacts of the commutator or timer 61 of a magneto 62 which is grounded as is customary in gas engine ignition systems. The armature shaft of this 95 magneto carries a beveled pinion 63 which meshes with a beveled pinion 64 mounted upon one end of a shaft 65 which extends radially through the wall of the crank casing and within the crank casing is journaled in a 100 bearing 66. The inner end of this shaft carries a second beveled pinion 67 which meshes with a beveled gear 68 carried by the crank shaft within the casing. If desired, this 105 beveled gear 68 and the pinion or spur gear 47, previously described, may be integrally formed.

110 Obviously, it is desirable to be able to advance and retard the timing of the spark in the various cylinders and for this reason I 115

provide an automatic spark controlling device, which is best shown in Fig. 1 of the drawings. This includes a supporting brace 69 which is preferably connected at its ends to adjacent cylinders and which, intermediate its length, carries an outwardly and radially extending shaft 70 upon which is slidably mounted a weight 71 which is normally held in innermost position by helical springs 72 surrounding the shaft and engaging between the weight and a collar 73 fixed upon the outer end of the shaft. A link 74 is connected at one end to the arm 75 of the commutator and at its other end to an arm 76 carried by the weight. Obviously, as the speed of the engine increases, the weight 71 will be thrown outwardly against the force of the spring 72 to turn the commutator and advance the spark in the usual manner. On the other hand, as the speed of the engine decreases, the spring 72 will force the weight inwardly and retard the spark.

The above described engine is of the air cooled type and the cylinders are preferably provided with heat dissipating or radiating blades or ribs 77 which are peripherally spaced about the cylinders, extending longitudinally of the cylinders and inwardly to a point near the center of the cylinder heads.

Inasmuch as the crank case and cylinders carried by it revolve about the fixed crank shaft at a high rate of speed, it is desirable that a suitable bracing and guarding structure be provided to strengthen the crank casting and cylinders and to, in a way, inclose them. Further it is advantageous that this combined guard and brace shall also act with the cylinders as a fly wheel. To accomplish this, I provide radially extending arms 78 which are connected at their inner ends to crank casing at opposite sides of each cylinder and at their outer ends to a relatively light fly wheel 79 which surrounds the engine, being spaced slightly beyond the outer ends of the engine cylinders, as clearly shown in the drawings. This fly wheel or guard is preferably made up of two semi-circular sections 80, the ends of which abut against each other and are secured by bolts 81 passed through the inwardly directed arms of L-shaped brackets 82 carried by the abutting ends of the sections 80 and which receive the nuts 83.

From the foregoing description of my gas engine, its operation will be readily understood. The crank casing and cylinders may be manually or otherwise turned about the crank shaft to cause a drawing in of explosive mixture from the supply pipe 51 through the various intake valves of the cylinders into the cylinders. The explosive mixture thus drawn in will be ignited in the cylinders in the regular order of firing by sparks which are timed by the magneto's commutator, in the usual manner, and the

burnt gases will be expelled from the cylinders through the exhaust pipe 58.

It will, of course, be clear that the guard and brace which act as a light fly wheel may be omitted and, as shown in Fig. 5, blades 70 may be fastened to the crank casing between the cylinders and the engine itself employed as a fan or propeller. In this case it would not be necessary to extend the sleeve 12 of the crank casing beyond the bonnet or hood 57 and the oil supply pipe 24 could communicate directly with the exposed end of the crank shaft 14. Under these circumstances, it will be obvious that various minor changes in construction may be made without the slightest degree departing from the spirit of my invention and I therefore reserve the right to make any changes, within the scope of the appended claims.

Having thus described the invention, what is claimed as new is:

1. In a rotary gas engine, a fixed crank shaft, a crank casing rotatably mounted about the shaft, radial cylinders carried by the casing, pistons in the cylinders operatively connected to the crank shaft, exhaust valve chambers, valves for controlling passage of exhaust gases from the cylinders to the valve chambers, a sleeve formed upon the crank casing and extending beyond one end of the crank shaft as a means for transmitting power, a hood fixed to the sleeve and providing an annular chamber, branch exhaust pipes leading from the valve chambers to the annular chamber, a second hood in which the sleeve is revoluble providing a chamber communicating with that of the first hood, and a main exhaust pipe leading from the second hood.

2. In a rotary gas engine, a fixed crank shaft, a crank casing revolvably mounted about the shaft, cylinders carried by the crank casing, pistons in the cylinders, operative connection between the pistons and crank shaft, the crank shaft at one end being formed with a longitudinal opening communicating at one end with the interior of the crank casing and formed at its other end with a radial branch opening through the crank shaft, a sleeve formed upon the crank casing and surrounding such end of the crank shaft and projecting beyond it to transmit power, said sleeve being formed interiorly with an annular chamber communicating with the radial branch of the passage of the crank shaft and with a radial passage opening into such chamber, and a bearing for the sleeve formed interiorly with an annular chamber communicating with the passage of the sleeve and with an oil supply duct communicating with such chamber.

3. In a rotary gas engine, a fixed crank shaft, a crank casing rotatably mounted about the shaft and having radial arms, cyl-

inders communicating with and extending from the arms, braces secured at their inner ends to diametrically opposed sides of the arms adjacent their juncture with the 5 cylinders and diverging from the arms at either side of the cylinders with their free ends oppositely bent, and a fly wheel secured.

to the oppositely bent ends of the braces and supported by them concentrically with respect to the crank case and cylinders and in 10 spaced relation to the outer ends of the cylinders.

In testimony whereof I affix my signature.
THOMAS L. ARTHUR. [L.S.]
